UNITED STATES PATENT OFFICE.

CHARLES THEINERT AND SIMON CHRISTIANSEN, OF NEW YORK, N. Y.

METHOD OF MAKING PLUSH ARTICLES OF CLOTHING.

SPECIFICATION forming part of Letters Patent No. 326,348, dated September 15, 1885.

Application filed April 11, 1885. (No model.)

To all whom it may concern:

Be it known that we, CHARLES THEINERT and SIMON CHRISTIANSEN, both of the city, county, and State of New York, have invented 5 certain new and useful Improvements in the Mode of Making Plush Articles of Clothing, of which the following is a full, clear, and exact description.

In uniting the parts or pieces for forming 10 plush articles the edges of said parts or pieces have been folded over toward the smooth sides of the pieces, and the pile faces of the folded parts of the two pieces brought in contact and united by stitches made through the said folded parts. Some of the hairs or pile-threads are 15 cut off when cutting the pieces by means of shears, and some are doubled and bent over by folding the edges. The seam can be seen distinctly on the pile side of the article and materially mars the appearance of the article. 20

The object of our invention is to avoid these difficulties, which we accomplish by cutting the pieces in a special manner, abutting the edges, and sewing the abutting edges together 25 by means of the glove-stitch.

Reference is to be had to the accompanying drawings, forming part of this specification, in which similar letters of reference indicate corresponding parts in all the figures.

30 Figure 1 shows the manner of cutting in relation to the warps and wefts. Fig. 2 is a detail view of two united pieces. Fig. 3 is a cross-sectional view of the same.

The piece of plush is placed on a table with 35 the pile side downward. The piece is then cut on the back by means of a knife, and in such a manner that the warp and weft threads *a b* are at an angle different from a right angle—that is, diagonally to the line of the cut—

that is, the warps and wefts are neither parallel nor at right angles to the line of the cut. 40

The pieces *A* are cut in this manner, so that the threads uniting the pieces, and which threads pass through the pieces near the edges, do not all hold on one or a few warp or weft 45 threads near the edges, but on numerous different threads, as is shown in Fig. 2. When the pieces *A* are cut in this manner, the stitches can be passed through the body of the piece very close to the edges, and the threads will 50 not rip the piece.

The cut edges of the pieces are abutted, as shown in Fig. 3, but not lapped or folded, and then stitched together by the glove-stitch or cross-stitch. The upper edges of the pile- 55 threads of the two united pieces are flush, and the seam does not appear on the plush surface of the article formed.

Our garment has invisible seams, whereas in the plush garments as usually made the 60 seams are indicated by a depression in the surface of the plush.

Having thus described our invention, we claim as new and desire to secure by Letters Patent— 65

In the art of making plush articles of clothing, the herein-described method, which consists in cutting the plush on the back by means of a knife diagonally to the warps and wefts, abutting the edges of the pieces, and uniting 70 them by the glove or cross stitch, substantially as herein shown and described.

CHARLES THEINERT.
SIMON CHRISTIANSEN.
